APPARATUS FOR CASTING RIBBONS OF
GELATIN AND THE LIKERex E. Moule, Holden, Mass., assignor to Norton
Company, Worcester, Mass., a corporation of
Massachusetts

Application March 5, 1949, Serial No. 79,743

2 Claims. (Cl. 18—15)

1

The invention relates to encapsulating apparatus and with regard to its more specific features to apparatus for casting ribbons especially of gelatin.

One object of the invention is to provide an efficient apparatus for congealing gelatin or other liquid to make ribbons thereof. Another object of the invention is to provide efficient apparatus for steadily removing the heat supplied to a rotating metal drum whereby a liquid flowed onto such drum will become a ribbon. Another object of the invention is to provide apparatus of the type indicated which will operate efficiently under various climatic changes and varying conditions of heat and humidity. Another object of the invention is to provide a simple and economical apparatus for keeping cool the casting drums of an encapsulating machine.

Other objects will be in part obvious or in part pointed out hereinafter.

In the accompanying drawings in which is shown one of various possible embodiments of the mechanical features of this invention,

Figure 1 is a front elevation of a capsulating machine having incorporated therein apparatus according to the present invention, certain mechanism of the capsulating machine being omitted.

Figure 2 is a sectional view taken along the line 2—2 of Figure 1.

Figure 3 is a fragmentary elevation of the rear of the machine.

Figure 4 is a vertical sectional view taken on the line 4—4 of Figure 1.

Figure 5 is a vertical sectional view through the axis of one of the tanks for the ribbon forming material.

Apparatus according to the present invention may be applied to many kinds of capsulating machines but as an illustrative embodiment of the application of the invention I will describe a particular machine, omitting however, those mechanisms which have no direct connection or association with the apparatus of the present invention.

Referring now to Figure 1, the machine has a base plate 10 which is braced by angle irons 11 and supported by legs 12 resting on a floor indicated by the dot-dash line 13. Extending upwardly from the base plate 10 and supported thereby is a large plate 14 which has front and rear vertical plane surfaces and serves as a support for many of the machine elements. A sheet metal casing 15 of inverted U-shape extends upwardly from either side of the base plate 10 and

covers the sides and the top of the machine but not the front and the rear, all as clearly shown in Figures 1, 2 and 3. This casing 15 is further braced by legs 16 at the front and rear of the machine, extending vertically from the base plate 10 to the underside of the top of the casing 15.

Referring now to Figure 3, an electric motor 20 has a casing which is rigidly connected to a casing having variable speed reducing mechanism 21 which drives a shaft 22 on which is a sprocket gear 23 driving by means of a sprocket chain 24 a sprocket gear 25 on a shaft 26. The shaft 26 extends into a casing having a speed reducing mechanism 27 from which extends an output shaft 28 on which is a sprocket gear 29 driving by means of a sprocket chain 30 a sprocket gear 31 on a shaft 32.

The shaft 32 extends into another casing having a speed reducing mechanism 33 which likewise has an output shaft 34 on which is a sprocket gear 35 driving by means of a sprocket chain 36 a sprocket gear 37 on a shaft 38.

The shaft 38 is journalled in a round portion 40 of and connected to a casing 41 which in turn is bolted to a casing 42. In the round portion 40 is a worm, not shown, which meshes with a worm wheel in the casing 41 likewise not shown. A shaft, not shown, upon which the worm wheel is fixed extends into the casing 42 in which is further gear reducing mechanism driving an output shaft 50. Thus between the motor 20 and the shaft 50 there are four speed reducing mechanisms; the casings 27, 33 and 42 are shown as bolted to the top of the base plate 10 while the casing 21 may be secured to the underside of the base plate 10. Detailed illustration of the gearing in these speed reducing mechanisms would seem to be superfluous since many types of speed reducing mechanisms are available on the market and the construction of such has nothing to do with the present invention.

Secured to the shaft 50 is a sprocket gear 51 which, by means of a chain 52 drives a sprocket gear 53 (Fig. 2) on a shaft 54. Secured to the shaft 54 is a sprocket gear 55 which, by means of a sprocket chain 56 drives a sprocket gear 57 on a shaft 58. The chain 56 is crossed so that the shafts 54 and 58 are rotated in opposite directions, but at the same speed because the gears 55 and 57 are of the same size. By reason of all the speed reducing mechanism and the difference in size of the gears 51 and 53, the shafts 54 and 58 turn very slowly taking from approximately one minute to sixteen minutes for one revolution. Referring now to Figures 1 and 2, the shafts

54 and 58 extend between journals 60 and the plate 14; they are also journalled in the latter. The journals 60 are supported by inverted U-shaped brackets 61 that are bolted to the base plate 10. Referring now to Figure 4, keyed to the shaft 54 is the hub 64 of a disc wheel 65 to the periphery of which is secured a metal cylinder 66, these parts together therefore forming a cylindrical drum wheel the front of which is closed but the back of which is open. On the shaft 58 is an identical cylindrical drum wheel the parts of which, where they are shown, being identified by the same numbers in Figures 1, 2 and 3.

Referring now to Figure 1, supported by the top of the casing 15 are a pair of tanks 70 for storage and delivery of the material in a liquid state which is to form the ribbons, this material being, in an illustrative example, gelatin. Pipes 71 extend into the bottom of the tanks 70 and have hand controlled valves 72 for allowing the liquid to flow, from time to time and as desired, into spreader boxes 73. These spreader boxes 73 may be of any usual or desired type for machines of this class. They allow a thin ribbon-like film of liquid to flow out upon the rotating wheels 66 through a rectangular orifice. The wheels 66 are cooled as will hereinafter be described and consequently the liquid, for example gelatin, congeals to a flexible solid thereby forming ribbons. The thickness of each ribbon can be varied by adjusting the vertical dimension of the orifice. Such spreader boxes are known in the art so need no further description herein and particular examples thereof may be found in U. S. Patent No. 2,379,831 and Patent No. 2,292,760. These spreader boxes 73 are held in position by the plate 14 but they rest upon the drum wheels 66.

Referring to Figure 1, the ribbons 80 are removed from the drums 66 by ribbon take-off rollers 81 rotatably mounted on spindles 82 and rotated by belts 83 which are driven by combination gear and pulley members 84, the gear portions of which are in engagement with gear teeth 85 (Fig. 4) formed on the rear edges of the surfaces of the drums 66. The combination gear and pulley members 84 are journalled on spindles 86 secured to and projecting forwardly from the plate 14.

Still referring to Figure 1, attached to and extending forwardly from the plate 14 are a pair of open top receptacles 90 which may contain oil, water, alcohol, carbon tetrachloride or anything else which will serve the purpose of lubricating the ribbons 80 depending on the material which is being cast into ribbons. These receptacles 90 may also contain electric heating elements 91 to keep the liquid in the receptacles 90 at such temperature as will heat the ribbons 80 to the optimum for encapsulating. As will be further described in detail, the drums 66 are continuously cooled and indeed they are continuously removing heat from the gelatin or other material which flows out of the spreader boxes 73, and by being cooled, forms the ribbons 80. Consequently, as the ribbons 80 move into the receptacles 90, they are below room temperature (assuming that the room where the machine is located is warm enough for comfortable working conditions) and by the continuous passage of ribbons through the receptacles 90 the liquid therein is being cooled; wherefore in order to raise the temperature of the ribbons 80 somewhat to the optimum temperature for encap-

sulating, I may provide the electric heating elements 91 to provide a continuous flow of heat (in small amount) to the liquid in the receptacles 90. However in the case of some materials and under some conditions I find it advisable to cool the liquid in the receptacles 90 instead of heating it. The ribbons 80 are guided into and out of the receptacles 90 by means of rollers 95, 96 and 97 all of which are rotatably mounted, the rollers 95 and 97 extending between lugs 98 and 99 respectively, there being two pairs of each, mounted on the front and back ends of the receptacles 90, and the rollers 96 being journalled in the end walls of the receptacles 90.

After leaving the rollers 97, the ribbons 80 pass over guide rollers 101 and then down between grooved tube forming rollers 102 which bring the ribbons 80 together and form them into tubes around a plurality of vertically extending arbor or mandrel pipes not shown which deliver filling material to the tubes thus formed which is the material in the capsules made by the machine. These rollers 102 are positively rotated and are journalled in a frame 103 secured to the plate 14. Below the rollers 102 are tube and capsule forming dies 105 which are mechanically reciprocated and there may be one pair or two pairs of these. Below the dies 105 are stripper members 107 and below these are intermittently operated take-up rollers 108. All of this mechanism for forming the capsules is diagrammatically illustrated herein, the details being not shown since they form no part of the present invention and are fully disclosed in my copending application Serial No. 48,912 filed September 11, 1948, now Patent No. 2,549,327 of April 17, 1951, a continuation of my application Serial No. 538,761 filed June 5, 1944 now abandoned. Since the present invention is concerned with apparatus for casting ribbons and for bringing them to the right condition for encapsulating operations, I do not deem it necessary fully to describe and illustrate the specific encapsulating mechanism herein since this may be varied at will.

The strippers 107 which may be of any suitable type remove the capsules 110 from the joined ribbons 80 which are now full of holes. The double perforated ribbon 111 moves downwardly where it is collected in any suitable box, not shown, and eventually is re-melted and charged into the tanks 70. There may be a long slot through the base plate 10 to permit passage of the double perforated ribbon 111.

The capsules 110 fall into wire trays 115 which are removably located in open top tanks 116 resting on and secured to the top of the base plate 10. In each tank 116 is a suitable liquid, preferably an oil such as kerosene, and this as will hereinafter be explained is cooled to a temperature which will usually be somewhat below 60° F. Dropping the capsules 110 into a cooled liquid has several advantages; in the first place it keeps the vitamins in the capsules from deteriorating by reason of being too warm, it being known that many vitamins lose their efficacy if they are not kept cool, and in the second place it prevents good capsules from being contaminated with the occasional capsule, perhaps one in many thousands, which breaks open and spills the liquid therein. The filling material for many capsules will stick to the outside of the capsules so tenaciously that it cannot be removed in any practical manner but if all the capsules immediately drop into an oil bath, no filling material can stick to the outside surface of any capsule.

Furthermore certain water soluble vitamins often discolor or dull the capsules by eating part way through the gelatin shell or even penetrate the shell completely. If the capsule, when first made, is dropped into a cold oil, the gelatin shell is quickly hardened to a strong and resistant condition capable of resisting the solvent action of such water soluble vitamins.

Still referring to Figure 1, I provide a refrigerating unit 120 which may be located anywhere, such as in the basement of the building or on top of the sheet metal casing 15 or elsewhere, being shown in the drawing as under the floor 13. This refrigerating unit 120 comprises a compressor 121 having a pulley 122, driven by a belt 123 from a motor 124 driving a fan 125 which blows air through a radiator 126, all of the above resting upon a suitable base 127 which also supports a tank 128. The motor 124 is conveniently an electric motor energized by any power usually available in shops. Any suitable fluid may be used in the refrigeration system but preferably one whose boiling point and latent heat characteristics are such as to make for efficiency, for example dichlor-difluor-methane.

This fluid, such as dichlor-difluor-methane, returns to the unit 120 through a pipe 130 in the form of a gas, and it is compressed by the compressor 121 (a cylinder containing a piston operated by crank and connecting rod and having the usual check valves) and is exhausted through a pipe 131 now in the form of a hot gas under compression and then enters the radiator 126 and works toward the bottom whereupon, due to cooling to not much above room temperature, it becomes a liquid and enters the tank 127 which is connected to the bottom of the radiator 126, this being a radiator like the familiar automobile radiator.

A pipe connection 133 is connected to the tank 128 and to this connection 133 is connected a pipe 134 to conduct the fluid, now liquid, to valves; the pipe 134 is connected by a T-union 135 to a pair of pipes 136 and 137. The pipe 137 leads to an expansion valve 138 which drops the pressure and causes the liquid to change partly into gas. The pipe 136 leads to another T-union 139 which is connected to a pipe 140 and a pipe 141; the former leads to an expansion valve 142 and the latter leads to an expansion valve 143 each of which may be the same as the valve 138 and each of which causes the pressure to drop and therefore changes the liquid partly into gas.

From the expansion valve 142 the fluid, now partly liquid and partly gas, goes by way of a pipe 145 to a coil 146 inside of the left hand drum wheel 66 and similarly from the expansion valve 143 the fluid goes by way of a pipe 147 to a coil 148 inside of the right hand drum wheel 66, these coils 146 and 148 being of the same construction. As shown in Figure 4, the coil 146 (and therefore also the coil 148) has many convolutions and fits inside the drum wheel near the cylindrical portion 66 thereof. The coils 146 and 148 are supported partly by the pipes 145 and 147 and partly by exhaust pipes 149 and 150 respectively and partly by brackets 151 as illustrated in Figure 4, these brackets 151 being secured to the plate 14.

From the expansion valve 138 the fluid goes by way of a pipe 155 to a coil 156 in the left hand tank 115 and thence by a pipe 157 to a union 158 to a pipe 159 and into a coil 160 in the right hand tank 116.

The exhaust pipes 149 and 150 are connected to a T-union 165 which is connected by a pipe 166 to a T-union 167 which is connected by a pipe 168 to a constant pressure valve 169 which is connected by a pipe 170 to a union 171 which is connected by a pipe 172 to a T-union 173 which is connected to the pipe 130. Similarly the coil 160 is connected to an outgoing pipe 175 which is connected to a T-union 176 which is connected by a pipe 177 to a constant pressure valve 178 which is connected by a pipe 179 to a union 180 which is connected by a pipe 181 to the T-union 173.

The latent heat of vaporization causes the fluid in the system to drop to a very low temperature after passing the expansion valves 138, 142 and 143 and in the coils 146, 148, 156 and 160 the fluid absorbs the heat thus cooling these coils to a low temperature and refrigerating the drums 66 and also the liquid in the tanks 116; thereby the fluid itself becomes hotter and being now all gas flows at a steady rate through the valves 169 and 178 back to the intake pipe 130. I may provide looped by-pass pipes 185 and 186 between the unions 167 and 171 in the case of the by-pass 185 and between the unions 176 and 180 in the case of the by-pass 186 which may be opened by turning bolts 187 and 188 respectively, these by-pass pipes being used if the constant pressure valves 169 and 178 or either of them break down.

The expansion valves 142 and 143 are controlled by bulbs 190 and 191 respectively and the expansion valve 138 is controlled by a bulb 192, these bulbs being connected by capillary pipes 194, 195 and 196 respectively to the valves 142, 143 and 138. The bulb 190 is strapped to the pipe 149, the bulb 191 is strapped to the pipe 150, and the bulb 192 is strapped to the pipe 175 and the temperature of these pipes near the refrigerating coils causes gas in the bulbs and in the capillary pipes to operate the expansion valves so that when the temperature of any bulb rises, the valve to which it is connected by the capillary pipe opens a little wider. The details of construction of the expansion valves as well as of constant pressure valves for use in refrigerating systems is known to the art so need not be further set forth herein. For the optimum casting of gelatin the drums 66 should be maintained at a temperature of between 40° F. and 60° F. by the refrigerating apparatus above described.

Successful encapsulating is dependent upon the physical condition of the ribbons 80 especially when these are gelatin ribbons. It has already been mentioned that in the receptacles 90 the ribbons 80 are heated somewhat; preferably they are heated to about room temperature, for example to about 70° F. although in certain cases they may be cooled instead of heated. Thus the temperature of the liquid in the receptacles 90 may vary between about 50° F. and 80° F. In order that the ribbons may weld to each other to form capsules, it is desirable that the contacting surfaces of the ribbons be fairly near the melting point of the material, for example in the case of gelatin it is desirable to bring the surface of the ribbons to around 95° F. without heating the ribbons all through. Consequently I may provide strip heaters 200 located between the guide rollers 101 and the tube forming rollers 102. In the case of gelatin the surfaces of the ribbons that are to come together should be heated to a temperature of between 85° F. and 100° F. for the best results.

But for the best results the outside surfaces of the ribbons 80 should, when the dies 105 operate, be no hotter than 80° F. and preferably not above 70° F. Furthermore, it is preferable in the case of most gelatins to have the contacting surfaces of the ribbons 80 as hot as 95° F.

Another conditioning which I have found to be desirable is the elimination of moisture from the ribbons 80, especially if they are gelatin ribbons and consequently I provide electric fans 201 mounted to blow air against the surfaces of the ribbons 80 when they are on the drums 66. It will be observed that the sides of the ribbons which are thereby dried are the outsides when they come together.

Referring now to Figure 4, I preferably provide means to assist the transfer of heat from the drums 66 to the coils 146 and 148. To that end electric motors 205 may be supported by brackets 206 secured to the rear of the wall 14 behind the drums 66 and have shafts 207 extending through the wall 14 upon which shafts 207 are secured pinion gears 208 meshing with ring gears 209 secured to fans 210 having several blades preferably with surfaces about parallel to the axes of the shafts 54 and 58 or radial to such axes to drive the air centrifugally. These fans 210 have hubs 212 which are journalled on the shafts 54 and 58 and located between spacing collars 213 and 214 on these shafts. As the fans 210 are rotated the air inside the drums 66 and between the disc wheels 65 and the plate 14 is driven through the coils 146 and 148 to the inside of the drums 66 thus cooling them, and the air then returns along the surfaces of the discs 65 and then axially to the spaces inside of the blades of the fans 210. The air is thus kept cold by circulation and heat is effectively transferred from the drums 66 to the coils 146 and 148. I find that it is desirable to keep this cold air from escaping from or, stated in another way, to keep outside warm air from entering the space enclosed by the drums 66 the wheels 65 and the wall 14, so therefore I preferably provide sealing gaskets 215 secured to the wall 14 and contacting the inside rear edges of the drums 66.

In case the ribbons 80 are of gelatin which is preferred for many capsules, it should be at a temperature between about 130° F. and 145° F. in the tanks 70 so that it may freely flow, so therefore I preferably provide heating means for the tanks 70 which may take the form, as shown in Figure 5, of heating elements 220 in a water compartment 221 just outside of the filling material chamber 222 of each tank 70. I may provide a further compartment 223 between the cylindrical outer wall of each tank 70 and the compartment 221 and this is preferably filled with insulating material. I may further provide a thermostat 224 to regulate the temperature of the water in the compartment 221 as desired. The heating elements 220 as well as the strip heaters 200 and the heating elements 91 may be modern type strip heaters comprising a metal sheath filled with fused magnesia and containing electric heating wires, this type of heating element being now commonly used for electric stoves. Such heating elements may be operated by readily available electric power at 110 volts, 60 cycles. It will be noted from Figure 5 that the chamber 222 is

cylindrical and has a bottom 225 which inclines toward the front of the machine. Each pipe 71 extends through the bottom of the tank 70 to the inside of the chamber 222 at the front thereof in order that the chamber 222 may be completely drained. Readily removable covers 226 are provided for the tanks 70 and filling and drain holes, not shown, are provided for the water compartments 221.

10 In case it is desired to cool the liquid in the receptacles 90 instead of heating it, the elements 91 are to be deemed to be lengths of pipe connected on one side to the pipes 145 and 147, and on the other side connected to the pipes 148 and 150.

15 While I have described refrigerating apparatus of the compressor type it should be understood that other types of refrigerating apparatus which will circulate coolant through the coils 146 and 20 148 may be used, such as gas absorption refrigerating apparatus.

25 One application of the invention involves a method of making capsules out of gelatin and water soluble vitamin so therefore, so far as this 25 method is concerned, the ribbons 80 are gelatin ribbons and the filling material is water soluble vitamin or vitamins.

30 It will thus be seen that there has been provided by this invention an apparatus in which the various objects hereinabove set forth together with many thoroughly practical advantages are successfully achieved.

35 As many possible embodiments may be made of the above invention and as many changes might be made in the embodiment above set forth, it is to be understood that all matter hereinbefore set forth or shown in the accompanying drawings is to be interpreted as illustrative and not in a limiting sense.

40 I claim:

1. In apparatus for casting ribbons of gelatin and the like, the combination with a receptacle to contain the material to be cast, a spreader connected to said receptacle and having an orifice to deliver said material, a casting drum to receive said material and means to rotate said casting drum, of means for cooling said casting drum comprising coils therein, means for circulating coolant through said coils, a rotatable fan inside of said casting drum positioned to drive air through said coils and against the inside of said casting drum, and means to rotate said fan.

50 2. In apparatus as claimed in claim 1, the combination with the parts and features therein specified, of a plate adjacent to said casting drum, and sealing gaskets connecting the plate to the drum to keep outside air from entering the drum.

REX E. MOULE.
